UNITED STATES PATENT OFFICE.

CHARLES ALDRICH, OF WEST PARIS, MAINE.

FOLDING SLED.

1,300,095.

Specification of Letters Patent.

Patented Apr. 8, 1919.

Application filed December 16, 1918. Serial No. 266,883.

To all whom it may concern:

Be it known that I, CHARLES ALDRICH, a citizen of the United States, residing at West Paris, in the county of Oxford and State of Maine, have invented certain new and useful Improvements in Folding Sleds; and I do hereby declare the following to be a full, clear, and exact description of the invention, such as will enable others skilled in the art to which it appertains to make and use the same.

This invention relates to sleds and more particularly to a folding, or collapsible sled.

It is one of the objects of the present invention to provide a simple, practical, inexpensive and substantial and collapsible sled and to provide means for locking the sled sides or frames in extended position when the parts are set for use.

With the above and other objects in view as will be rendered manifest in the following specification with relation to the embodiment of the invention illustrated in the accompanying drawing, the invention consists in the construction, combination, and in details and arrangement of parts as more particularly hereinafter described.

In the drawing,

Figure 1 is a perspective view of the extended sled adjusted for use.

Fig. 2 is a perspective view of the sled showing it in collapsed position.

Fig. 3 is a bottom plan view of the extended sled frame, and,

Fig. 4 is a detail fragmentary view of the knuckle-joint of the brace.

The sled comprises a pair of side or frame members 2—2 which may be of suitable material of any desired proportion and dimension, these sides being connected by a series of transverse links 3, which are arranged in pairs as clearly shown in Fig. 1. The transverse links are pivotally connected to the sides or frames and are adapted to swing in parallelism so as to separate the frames or sides from each other, as shown in Fig. 1, as to permit the collapsing of the sled to the position shown in Fig. 2.

While the sides or frames may be constructed in various manners, as illustrated each side or frame comprises a runner 5,

having its front and rear ends turned up at 6 and 7, to be secured to the upper portion of perpendicular pins 8, a suitable number of which is provided along the top surface of 55 the runner 5 of each side or frame. The upper ends of the pin may be turned down, as clearly shown in Fig. 1, to receive the ends of the pairs of links. Extended along and mounted upon the pegs or pins on each 60 runner, is a top or rail member 9, forming a portion of the side or frame 2, and in the illustration of my invention the rails or top members 9 are interposed between the respective links of each pair, where they are 65 mounted on the pins. The links or assembled elements may be prevented from having longitudinal movement along the pin by any suitable fastening means as for instance, cotter pins 10.

For the purpose of locking the swinging or pivotally connected sides or frames 2—2 in extended position I provide a simple knuckle-jointed link 11, the ends of which are pivoted at 12 and 13, at diagonally opposite points to certain sets of pairs of links. When the side frames are spaced as shown in Fig. 1, the link 11 occupies a diagonal position and for the purpose of collapsing the sled the link may be broken about its 80 pivot 15 at the knuckle 14, so that the sections will swing with respect to each other.

I claim:

1. A laterally collapsible sled comprising side frames, a series of parallel pairs of superposed links connecting the frames transversely at their upper portions and upon which they may swing, and means for locking the frames in extended relation.

2. A laterally collapsible sled, comprising 90 side frames, pairs of links connecting the frames transversely at their upper portions and upon which they may swing, and means for locking the frames in extended relation, the links of each pair being spaced by components of the frames.

3. A laterally collapsible sled comprising side frames, each having a runner with a series of perpendicular pins on its upper face, the ends of each runner bent up and 100 secured to the upper part of the pins, rails mounted on the pins and forming parts of

the frames, pairs of links pivoted on the pins of and connecting the frames, and means for locking the extended frames.

4. A laterally collapsible sled comprising side frames, each having a runner with a series of perpendicular pins on its upper face, the ends of each runner bent up and secured to the upper part of the pins, rails

mounted on the pins and forming parts of the frames, pairs of links pivoted on the pins of and connecting the frames, and means for locking the extended frames, the links of each pair being spaced by the interposed rails. ¹⁰

In testimony whereof I affix my signature.
CHARLES ALDRICH.
